AIR PUMP

Orlando B. Johnson, Boise, Idaho

Application February 6, 1936, Serial No. 62,684

5 Claims. (Cl. 230—174)

This invention relates to compressors, an important object of the invention being to provide a compressor so constructed that substantially large inlet valves may be used, thereby providing an especially desirable and efficient valve structure for use with high speed compressors, eliminating the use of small valves which necessarily reduce the velocity of the air being drawn into the compressor. Another object of the invention is to provide a structure wherein the compressed air will have a more direct and unobstructed outlet thereby reducing the power necessary for the operation of the device, to a minimum.

A further object of the invention is to provide a compressor constructed in such a way that the stationary piston thereof may be supplied with cooling liquid maintaining the piston and cylinder cool at all times.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a longitudinal sectional view through a compressor illustrating the construction of the piston wherein a cooling fluid flows through the piston.

Figure 2 is a longitudinal sectional view through the compressor, taken on line 2—2 of Figure 1.

Figure 3 is an end elevational view of the compressor.

Figure 4 is a sectional view taken on line 4—4 of Figure 2.

Figure 5 is a longitudinal sectional view through a modified form of compressor.

Figure 6 is a sectional view taken on line 6—6 of Figure 5.

Figure 7 is an end elevational view of the compressor.

Figure 8 is a sectional view taken on line 8—8 of Figure 6.

Figure 9 is a longitudinal sectional view through a further modified form of compressor.

Figure 10 is a sectional view taken on line 10—10 of Figure 9.

Figure 11 is a sectional view taken on line 11—11 of Figure 9.

Figure 12 is a longitudinal sectional view

through a still further modified form of compressor.

Referring to the drawings in detail, the reference character 5 designates a compressor cylinder, which is provided with removable heads 6. 5 Disposed substantially centrally of the heads 6, are intake valves 7 which are substantially large, to admit a large quantity of air with each stroke of the cylinder. These valves are formed with valve stems 8 that move through openings in the arms 9 that are formed integral with the heads 6. Coiled springs are mounted on the stems 8 and normally urge the valves 7 to their closed positions.

Disposed within the cylinder 5 is a piston 11 15 which is hollow and supplied with an inlet pipe 12 and an outlet pipe 13 communicating with the interior of the piston. In this form of compressor the cylinder is horizontally disposed and the upper inner surface of the piston is inclined upwardly towards the outlet pipe 13, as clearly shown by Figure 1 of the drawings, with the result that water entering the piston, will be directed upwardly to the outlet pipe 13, thereby creating a circulation within the piston to cool 25 the piston.

A valve opening is formed in each end of the piston, and these openings are provided with valve seats 14 against which the valves 15 seat, the valves being of a construction to permit air 30 to pass into the pipe 16 which has enlarged ends surrounding the valve openings. Communicating with the pipe 16 is a pipe 17 that extends from the piston at a point intermediate the ends of the piston, the pipe leading to a suitable compressor tank, not shown. Directly opposite to the pipe 17 is a supporting bar 18, the bar 18 and pipe 17 being connected to the support 19, by means of the straps 20.

Elongated openings 21 are formed in opposite 40 sides of the cylinder 5, through which the pipes 17 and supporting bar 18 extend and permit reciprocation of the cylinder, over the piston. A connecting yoke 21' is secured at one end of the cylinder, through which yoke the movement may 45 be imparted from a suitable power device, to the cylinder. Thus it will be seen that as the cylinder is reciprocated over the piston, air will be drawn into the pipe 16 at one end thereof and with the return stroke of the cylinder air will 50 be forced into the opposite end of the pipe 16, forcing the air through the pipe 17 to the compressor tank.

In the form of the invention as shown by sheet 2 of the drawings, a compressor cylinder 55

is indicated by the reference character 22, the compressor cylinder having elongated openings 23 in opposite sides thereof, to accommodate the pipes 24 that extend into the piston 25 supplying cooling liquid to the interior of the piston to maintain the piston cool.

One end of the cylinder is closed by the head 26 which is formed with a valve opening to accommodate the valve 27 which operates when suction is created within the cylinder, due to the operation of the cylinder and the piston.

The piston 25 is provided with an intake valve 28 through which air passes, when the cylinder moves to a position as shown by Figure 6 of the drawings. At the opposite end of the piston is a valve 29 that operates in the opposite direction, the valves 26 and 29 being mounted in enlargements formed at the ends of the pipe 30. It will be seen that the valves 28 and 29 are so arranged that air may pass directly through the pipe 30, when the cylinder is moved in one direction only.

A pipe indicated by the reference character 31 is provided with an enlarged end portion 32 providing a valve housing for the valve 33 which is operated by the air pressure in one end of the cylinder, allowing air to pass through the pipe 31 and through the pipe 34, to the air compressor tank not shown.

30 In Figures 9 and 10 the reference character 35 indicates a compressor cylinder which operates over the piston 36, the piston 36 being provided with an inlet pipe 37 through which cooling liquid passes to the piston. This pipe 37 is supported within the outlet pipe 38, which is slightly larger than the inlet pipe 37, providing a passageway between the pipes to allow the cooling liquid to pass upwardly and away from the piston, after it has accomplished its purpose. A head 39 is formed at the lower end of the pipe 38, which head is provided with a plurality of openings 40 allowing the cooling liquid to pass into the pipe 38.

45 Mounted within the piston 36 is a pipe 41 formed with enlargements 42 at its ends, the enlargements housing valves that admit air to the pipe 41 when the cylinder 35 operates thereover, but prevent air from passing from the pipe 41, through the valves in the ends of the pipes.

50 A pipe 43 connects with the pipe 41 at a point substantially intermediate the ends of the pipe 41 and provides an outlet for the air entering the pipe 41. A supporting rod 44 connects with the piston 36 and is bolted to the support 45, whereby the piston is held in its operative position at all times.

55 Mounted within one end of the cylinder 35 is a valve 46 that operates through the suction of the cylinder operating over the piston to admit air to the cylinder.

60 In the form of the invention as shown by Figure 12 of the drawings, the cylinder 47 is disposed vertically, and is provided with elongated openings 48 that accommodate the pipes 49 connected with the piston 50.

65 These pipes 49 communicate with pipes 51 that have their open ends disposed adjacent to opposite ends of the piston so that a cooling fluid may be directed to the interior of the piston to maintain the piston cool at all times. In this form of the invention the pipe 52 through which air passes, is supported within the piston and has enlarged ends providing valve housings for valves which admit air to the pipe at each 70 stroke of the cylinder. Communicating with the

pipe 52 is an outlet pipe 53 that directs air compressed, to a suitable compressor tank.

In each end of the cylinder is an intake valve 54, which valves operate to admit air to the cylinder, with each stroke of the cylinder.

From the foregoing it will be seen that I have provided an air compressor wherein the cylinder reciprocates over its piston to the end that pipes leading to the interior of the piston may supply cooling liquid to the piston, maintaining the piston and cylinder cool at all times.

10 It might be further stated that it is within the scope of the invention to provide a suitable drain valve to drain the air pipes of any condensation or liquid which may collect therein. It is further pointed out that suitable means 15 may be provided for lubricating the piston, reducing wear and friction to the minimum.

Having thus described the invention, what is claimed is:

20 1. A compressor of the class described, comprising a stationary hollow piston, a pipe extending through the piston, an inlet valve in one end of the pipe, an outlet valve in the opposite end of the pipe, a cylinder operating over the piston and having inlet valves in the ends thereof, means for directing cooling liquid to the interior of the piston, and a connecting rod connected to the cylinder whereby the cylinder may be operated.

25 2. A compressor of the class described, comprising a hollow piston, a cylinder adapted to reciprocate over the piston, inlet valves disposed in the ends of the cylinder, a longitudinal pipe extending through the piston, an inlet valve in one end of the pipe and an outlet valve in the opposite end of the pipe, a connecting rod connected with the cylinder by means of which the cylinder is reciprocated over the piston, and means for directing cooling liquid to the interior of the piston.

30 3. A compressor of the class described, comprising a hollow piston, a cylinder adapted to reciprocate over the piston, inlet valves mounted in the ends of the cylinder, a pipe extending longitudinally through the piston, valves in the ends of the pipe and adapted to control the passage of air through the pipe, an outlet pipe connected with the first mentioned pipe, means for directing cooling liquid to the piston, and a connecting rod connected to the cylinder and adapted to reciprocate the cylinder over the piston.

35 4. A compressor of the class described, comprising a hollow piston, a cylinder adapted to reciprocate over the piston compressing air, a pipe extending through the piston, the ends of the pipe communicating with the spaces at the ends of the cylinder whereby air is compressed when the cylinder operates over the piston, and means for directing cooling liquid to the interior of the piston.

40 5. A compressor of the class described comprising a hollow piston, a cylinder adapted to reciprocate over the piston compressing air, a pipe extending longitudinally through the piston, valves in the ends of the pipe controlling the passage of air through the piston, a pipe extending into the piston and connected with the piston at a point intermediate the ends of the piston, supplying cooling liquid to the interior of the piston, an outlet pipe extending into the piston whereby cooling liquid may pass from the piston, and the inner surface of the piston being inclined towards the outlet pipe, directing cooling liquid to the outlet pipe.
